E. KRAEMER & G. SCHULER.

SHADE ROLLER.

APPLICATION FILED OCT. 21, 1916.

1,225,338.

Patented May 8, 1917.

UNITED STATES PATENT OFFICE.

EMIL KRAEMER AND GEORGE SCHULER, OF WOODSIDE, NEW YORK.

SHADE-ROLLER.

1,225,338.

Specification of Letters Patent.

Patented May 8, 1917.

Application filed October 21, 1916. Serial No. 126,818.

To all whom it may concern:

Be it known that we, EMIL KRAEMER and GEORGE SCHULER, both citizens of the United States of America, residing at Woodside, 5 county of Queens, State of New York, have invented certain new and useful Improvements in Shade-Rollers, of which the following is a full, clear, and exact description.

This invention relates to improvements in shade-rollers, the object being to provide a shade-roller that can be fitted to window-frames of different widths. In other words, our improved shade-roller includes a spindle which is adjustable longitudinally of the 15 casing therefor, said casing being in practice a shade-roller. To arrange our shade-roller for window-frames of various sizes, we provide a longitudinally adjustable one-piece spindle, to which one end of a spring 20 is secured, the opposite end of said spring being secured to the roller. In one embodiment of our invention, the spring is arranged to normally force the spindle outwardly, hence in order to attach the shade-roller to window frames of different widths, 25 it is but necessary to adjust the longitudinally movable spindle. In another embodiment of our invention, the spindle may be arranged to be forced inwardly by the 30 spring.

We will now proceed to describe our invention in detail, the essential features of which will be summarized in the appended claims, reference being had to the accompanying drawing, forming part hereof, 35 wherein:

Figure 1 is a longitudinal sectional view of our improved shade-roller;

Fig. 2 is an enlarged cross-sectional view, 40 the section being taken on a line 2--2 in Fig. 1;

Fig. 3 is a longitudinal sectional detail view of the cap of the shade-roller, the section being taken on a line 3--3 in Fig. 2;

Fig. 4 is a cross-sectional detail view on line 4--4 of Fig. 2 of the pawl carrying element of our improved shade-roller;

Fig. 5 is a cross-sectional view, the section being taken on a line 5--5 in Fig. 1, showing 50 the slots in the shade-roller to receive the ribs carried by the cap;

Fig. 6 is longitudinal sectional view, partly in elevation, of another embodiment of our invention; and

Fig. 7 is a fragmentary sectional detail

view, the section being taken on a line 7--7 in Fig. 1.

As herein embodied, our improved shade-roller consists of a shade-carrying casing 7 having a central chamber or bore 8 which extends longitudinally thereof for the greater part of its length, said chamber having in communication therewith a somewhat smaller bore or chamber 9 to receive the inner end of a spindle 10. The spindle 10 is herein illustrated as tubular, but may be solid if desirable. The spindle 10, whether tubular or solid, is provided with longitudinal grooves 11 to be engaged by the pawls or dogs 12 which are carried by a plate 13 which is loosely fitted to and surrounds the spindle 10.

To one end of the casing 7, we secure a cap 14 which is carried by a turned down or reduced portion 15 of the casing 7, provided with slots 18 to receive the ribs 19 on said cap; (see Fig. 5). The ribs 19 are formed by striking down a portion of the wall of the cap 14 and serve as keys to engage the recesses 20 in the pawl-plate 13, whereby said plate is held against rotation.

As can be seen in Fig. 1, the plate 13 is located in the chamber 21, formed by the cap 14 and partly inserted end of the casing 7. To keep the plate 13 in position we provide the side-wall of the cap 14 with stops 22 laterally expanded from the outer ends of the ribs 19 (see Fig. 3). The plate 13 as shown by dotted lines in Fig. 3 is located between the stops 22 and supplemental stops 22^a on the cap (see dotted line Fig. 3), whereby longitudinal displacement of the plate 13 is prevented. The plate 13 and cap 14 are provided with flanges 24 and 25, respectively, around the openings therein, through which the spindle 10 passes, to serve as bearings for the spindle 10.

To effect an outward movement of the spindle 10, when the roller is removed from the brackets 26 and 27, we provide a spring 28, the spring normally extending the spindle outwardly, the inner end of the spring being secured to the spindle 10 at 27^a, the outer end being secured to the plate 13. To secure the outer end of said spring to said plate, we provide eyes 28^a (see Figs. 2 and 4) formed by striking out some of the material of said plate. The free end of the spring is passed through the eyes 28^a, and clenched.

One end of the casing 7 carries a threaded adjustable trunnion 29, having a rounded portion 30 to engage the opening 31 in the bracket 27. The adjustable trunnion 29 permits the shade-roller to be centered relative to the window-frame. The spring 28 may be arranged to normally extend the spindle 10, or to normally retract same. To adapt the spindle 10 for engagement with the bracket 26, to prevent the premature withdrawal thereof, we may split the end thereof as at 47^a and expand or spread the split end to form yieldable projections 48^a, which can be forced through the opening 32 in the bracket 26. The expanded end of the spindle 10 will prevent the premature withdrawal thereof when the spring 28 is arranged to normally retract the spindle 10. To prevent the rotation of the spindle 10 when the casing is rotated, we provide the bracket 26 with projections 49^a extending into the opening 32 to engage the grooves 11 in the spindle 10 (see Fig. 7).

When the casing 7 is rotated, the spring 28 will be wound up, and retained in a wound up or partly wound up condition by the pawls or dogs 12 in the usual manner. To prevent the spindle 10 from being forced too far outwardly, when the roller is removed from its brackets, we provide a stop pin 33 (Fig. 1) which will strike the flange 24 on the plate 13 and limit the outward movement of the spindle 10.

In the form of our invention shown in Fig. 6, the casing 34 is provided with a chamber 35 containing a spring 36 surrounding a spindle 37. The spring 36 may be secured at one end thereof to the casing 34 at 38, the opposite end of the spring being secured to the spindle 37 at 39. The spring 36 may be arranged to normally extend or to normally retract the spindle 37. The spindle 37 is provided with grooves 40 extending longitudinally thereof to be engaged by pawls mounted on a plate located in the cap 41. The cap plate and pawls employed in this latter embodiment of our invention will be the same as illustrated in Fig. 1; hence, a detailed showing thereof has been omitted. In this latter embodiment of our invention we provide the outer end of the spindle 37 with notches 42 to engage the side-walls 43 of a jaw in a bracket 44, to prevent the rotation of said spindle. The opposite end of the casing 34 carries a cylindrical trunnion 45 similar to the trunnion 30 in the form illustrated in Fig. 1, rotatably engaging a bracket 46. To adjust the roller to a window-frame of greater width than the roller is arranged for, the spindle 37 will be moved longitudinally of the casing and the notches 42 caused to engage the bracket 44.

What we claim as our invention is:

65 1. In a shade roller, a longitudinally mov-

able spindle, in combination with a casing containing the same but permitting such movement of the spindle through the end of the casing, means carried by the protruding end of said spindle to engage a fixed bracket, 70 a spring surrounding said spindle and attached thereto at one end, the other end being relatively fixed within said casing, the said spring acting to cause the longitudinal movement of the spindle and also serving to 75 rewind the roller, and the bracket-engaging means carried by the spindle maintaining the latter in its longitudinally adjusted position against the tension of the spring after said spindle has been longitudinally adjusted.

2. A shade-roller consisting of a casing adapted to be rotatably supported at one end thereof by a bracket, a spindle carried by said casing and the outer end of which 85 is adapted to be engaged by a bracket arranged to prevent the rotation thereof, a spring within the casing secured to said spindle at one end thereof, a plate located at one end of said casing surrounding said spindle but free to rotate thereupon, means connecting said plate and said casing, means to connect the outer end of the spring to said plate, pawls carried by said plate to engage said spindle, said spring acting to move 95 said spindle longitudinally of the casing and means to prevent said plate from moving longitudinally of said spindle under the action of said spring.

3. In a shade-roller, a casing, a spindle carried thereby provided with grooves longitudinally thereof, a cap carried by said casing at one end thereof, the end wall of said cap being spaced from the adjacent end of said casing to provide a chamber, a plate located in said chamber provided with an opening for the free passage of said spindle, pawls carried by said plate to engage the grooves in said spindle, means carried by the cap to engage said plate, and a spring 100 connected at one end thereof to said plate, the other end of said spring being connected to said spindle.

4. In a shade-roller, a casing, a cap at one end thereof, the end of said cap being spaced from the adjacent end of said spindle to form a chamber, longitudinal ribs carried by said cap, a plate within said chamber provided with recesses to engage said ribs, said plate being provided with a central opening, a spindle passing loosely through the opening in said plate and through said cap, the spindle having grooves longitudinally thereof, pawls carried by said plate engaging the grooves in said spindle, and a 110 spring secured at one end thereof to said spindle.

5. In a shade-roller, a casing, a cap at one end thereof, the end of said cap being spaced from the adjacent end of said spindle to 115 120 125 130

- form a chamber, longitudinal ribs carried by said cap, a plate within said chamber provided with recesses to engage said ribs, said plate being provided with a central 5 opening, a spindle passing loosely through the opening in said plate and through said cap, the spindle having grooves longitudinally thereof, pawls carried by said plate engaging the grooves in said spindle, a 10 spring secured at one end thereof to said plate, the other end of said spring being secured to said spindle, and means carried by said cap to prevent the longitudinal displacement of said plate.
- 15 6. In a shade-roller, a casing, a cap at one end thereof, the end of said cap being spaced from the adjacent end of said spindle to form a chamber, longitudinal ribs carried by said cap, a plate within said chamber 20 provided with recesses to engage said ribs, said plate being provided with a central opening, a spindle passing loosely through the opening in said plate and through said cap, the spindle having grooves longitudinally thereof, pawls carried by said plate 25 engaging the grooves in said spindle, a spring secured at one end thereof to said plate, the other end of said spring being secured to said spindle, said spring acting to 30 constantly exert pressure to move the spindle longitudinally of the casing and to rewind the casing, and a plurality of stops carried by the cap, said plate being located between said stops.
- 35 7. In a shade-roller, a casing provided with slots at one end thereof, a cap located at the slotted end of said casing, the end of
- said cap being spaced from the slotted end of said casing to provide a chamber, longitudinal ribs carried by said cap and engaging the slots in the end of said casing, a spindle within said casing passing through said cap, pawls located within said chamber to engage said spindle, means connecting said pawls and cap, and a spring connecting 40 said casing and spindle.
8. A cap for a shade roller consisting of an end wall and a cylindrical side wall, the latter being provided with two sets of inwardly projecting stops and with longitudinal guiding ribs and the end wall having a central flanged opening for the passage of a spindle, a plate having a central opening alining with said opening in the end wall and recessed peripherally to fit said ribs, 50 the said plate being located between the said two sets of stops to prevent its motion in either direction longitudinally of the roller.
9. In a shade-roller, a casing, a longitudinally movable spindle carried thereby, said spindle being split at one end thereof, said split end being spread to form yieldable projections to engage a bracket and said roller being adapted to permit the longitudinal movement of the spindle.

Signed at New York city, N. Y., this
18th day of October, 1916.
